US0D1058972S

(12) **United States Design Patent** (10) **Patent No.:** **US D1,058,972 S**
(45) **Date of Patent:** **** Jan. 21, 2025**

(54) **PORTABLE EXTRACTION CLEANER**

(71) Applicant: **BISSELL Inc.**, Grand Rapids, MI (US)

(72) Inventors: **Tyler L. DeBeck**, Jenison, MI (US);
Nicholas Weigel, Rockford, MI (US)

(73) Assignee: **BISSELL Inc.**, Grand Rapids, MI (US)

(**) Term: **15 Years**

(21) Appl. No.: **29/857,662**

(22) Filed: **Oct. 25, 2022**

(51) LOC (15) Cl. **15-05**

(52) U.S. Cl.

USPC **D32/18**

(57) **CLAIM**

The ornamental design for a portable extraction cleaner as shown and described.

DESCRIPTION

FIG. 1 is a front isometric view of a portable extraction cleaner;

FIG. 2 is a rear isometric view of the portable extraction cleaner of FIG. 1;

FIG. 3 is a front elevation view of the portable extraction cleaner of FIG. 1;

FIG. 4 is a rear elevation view of the portable extraction cleaner of FIG. 1;

FIG. 5 is a left side view of the portable extraction cleaner of FIG. 1;

FIG. 6 is a right side view of the portable extraction cleaner of FIG. 1;

FIG. 7 is a top view of the portable extraction cleaner of FIG. 1; and,

FIG. 8 is a bottom view of the portable extraction cleaner of FIG. 1.

The broken lines represent structure or features that form no part of the claimed design.

1 Claim, 8 Drawing Sheets
